Attorney

UNITED STATES PATENT OFFICE.

OSCAR C. BERNARD, OF EL PASO, TEXAS.

COIN HANDLER.

Application filed November 1, 1923. Serial No. 672,147.

To all whom it may concern:

Be it known that I, OSCAR C. BERNARD, a citizen of the United States, residing at El Paso, in the county of El Paso, State of Texas, have invented certain new and useful improvements in Coin Handlers; and I do hereby declare the following to be a full, clear, and exact description of the invention, such as will enable others skilled in the art to which it appertains to make and use the same.

This invention relates to new and useful improvements in coin handling devices.

One object of the invention is to provide a device of this character which is especially adapted for use on counters, of stores, where the counters become soiled and coins placed thereon become soiled and render it inconvenient and distasteful for a customer to pick up his change. Also, a customer having gloves on the hands, finds it inconvenient, if not impossible to pick up coins from a counter, especially if the counter be the top of a show-case. This is also true with bare hands.

The present device is adapted to be disposed on a counter or show-case top, and includes a hopper into which the coins are placed, together with a means operable by the customer to easily, quickly, and conveniently remove the coins from the hopper, without danger of the coins coming into contact with the counter or show-case top.

Other objects and advantages will be apparent from the following description when taken in connection with the accompanying drawing.

In the drawing:

Figure 1 is an elevation of a coin handling device made in accordance with the invention.

Figure 2 is a vertical central sectional view on the line 2—2 of Figure 1.

Figure 3 is a side elevation of the device.

Figure 4 is a vertical central sectional view on the line 4—4 of Figure 3, the slideable tube being raised to permit the opening of the coin supporting doors, and the falling of the coins into the hand of a customer.

Referring particularly to the accompanying drawing, 10 represents a base, which is of any suitable size and material, but preferably of wood or enameled metal, and secured to the base, at diametrically opposite points, are the upwardly and inwardly ex-

tending supporting arms 11, the upper extremities of which diverge and are secured to the opposite inclined sides of the hopper 12. The front and top of this hopper are open, and in the front opening there is secured a transparent plate 13, permitting a view of the interior of the hopper. The lower end of the hopper is also open, and has the vertically and downwardly extending neck portion 14, to which is secured the upper end of a guiding member 15. The opposite sides of this member 15 are formed with the vertical longitudinal slots 16, while the upper edge of the front wall of the guide is formed with a notch 17 receiving the lower end of the transparent front plate 13, of the hopper.

Pivotedly secured to the lower end of each side of the extending neck portion 14 is a door 18, said doors being of such dimensions as to completely cover or close the lower end of the neck portion when in horizontal position. Extending outward from the hinged end of each of the doors 18 is a lug 19 which plays within one of the slots 16 of the guiding member, and whereby the door is permitted free pivotal movement, in the operation of the device, as will be more clearly explained hereinafter.

Slidable vertically on the neck portion 14 is a tubular member 20, the upper edge of the front wall of which is formed with an inwardly directed lug 21, which plays within said notch 17, and on the lower wall of which the said lug 21 is adapted to rest when the tubular member 20 is in its lowermost position. In the opposite sides of the tubular member 20 there are formed the elongated, transversely extending, slots 22, the lugs or ears 19 resting against the inner faces of the side walls of the tubular member, immediately above the said slots, when the doors are in closed position, and the tubular member in lowered position.

Coin placed in the hopper fall into the closed doors 18, and are supported thereby. To remove the coins the customer simply places the hand beneath the lower end of the tube 20 and gently lifts the tube causing the same to slide upwardly on the guide 15. The upward movement of the tube 20 causes the slots 22 to come opposite the ends of the lugs 19, when the lugs will pass outwardly therethrough, with the result that the doors 18 will gravitate into open position, dumping the coins into the hand of the customer.

Upon release of the tubular member 20 said member will gravitate to the position where its lug 21 engages with the lower wall of the notch 17. This downward movement of the tube 20 causes the lugs 19 to be withdrawn into the tube, whereupon they are engaged by the inner face of the tube and the doors swung upwardly into horizontal closed, and coin supporting position.

10 Thus neither the salesman nor the customer need place coins on a dirty or soiled and wet counter or show-case, with the result that the coins are maintained in a clean condition, with the obvious sanitary result.

15 What is claimed is:

1. A coin handler including a hopper having a depending discharge neck, coin supporting doors pivoted in the upper portion of the neck and having obtuse angularly extending projections disposed through the opposite sides of the neck, and a tube slideable on the neck and having slots receiving the projections therethrough for movement of the latter to swing the doors into and 25 out of coin supporting position.

2. A coin handler including a hopper having a discharge neck, doors pivotally supported in the neck and having obtuse angularly extending projections at one side of the

30 pivots, and a slideable tube on the neck having slots receiving the projections upon movement in either direction to open and close the doors, said projections being arranged to engage the unslotted portion of the tube, when said tube is at one limit of 35 its movement to maintain the doors in closed position.

3. A coin handler including a hopper having a depending discharge neck formed with 40 openings in the opposite sides thereof, doors pivotally supported in the upper portion of the neck and each having an obtuse angularly extending projection movable within an opening of the neck, and a vertically slideable tube on the neck having slots in opposite sides through which the said projections move to rock the doors into and out of open 45 position upon movement of the tube on the neck, said projections bearing against the tube, when the tube is in lowered position 50 to maintain the doors in closed coin supporting position.

In testimony whereof, I affix my signature, in the presence of two witnesses.

OSCAR C. BERNARD.
